UNITED STATES PATENT OFFICE.

BENJAMIN F. COPP, ALBUQUERQUE, NEW MEXICO.

KEY HOLDER.

Application filed February 28, 1927. Serial No. 171,617.

This invention relates to a key holder, one of the objects being to provide a simple and inexpensive device of this character which can be readily stamped from sheet metal 5 and conveniently carried in the pocket, means being employed whereby keys can be properly housed therein but readily swung therefrom into proper position for use, the housing or body portion of the holder serving to hold an extended key to position where it can be properly inserted into a lock.

A further object is to provide a device of this character which can be used as an 15 advertising novelty, ample space being provided for the reception of an advertisement.

A still further object is to provide a holder in which a key can be easily placed and from which it can be easily detached 20 when desired although, under ordinary conditions, the key is firmly retained against displacement.

With the foregoing and other objects in view which will appear as the description 25 proceeds, the invention resides in the combination and arrangement of parts, and in the details of construction, hereinafter described and claimed, it being understood that changes in the precise embodiment of the 30 invention herein disclosed may be made within the scope of what is claimed without departing from the spirit of the invention.

In the accompanying drawings the preferred form of the invention has been shown.

35 In said drawings,

Figure 1 is a side elevation of the holder, two keys being shown housed therein.

Figure 2 is a section on line 2—2, Figure 1, the keys being shown in plan.

40 Figure 3 is a section on line 3—3, Figure 1.

Figure 4 is a detail view of a blank from which the holder is formed.

Referring to the figures by characters of 45 reference 1 designates side plates simulating opposed sides of the handle of a pen-knife, these plates being connected by an integral web 2. The plates are preferably bowed transversely so as to present rounded outer surfaces and the ends are also preferably curved laterally. This form of the plate has been illustrated in Figures 2 and 3. Studs 4 are secured to the inner side of one of the plates 1 near the ends thereof and the 50 end portions of the other plate 1 are provided

ed with depressions 5 into which the free ends of the studs 4 are adapted to project when the blank is bent to proper shape. The outer surface of one of the side plates 1 has a groove 6 near its free longitudinal edge 60 while an opening 7 is formed at a corresponding point in the other side plate 1. This opening is adapted to receive a tongue 8 provided at one end of a plate 9 constituting a retaining clip, said tongue being 65 rounded so as to constitute a hinge connection between the clip and the side plate. Another tongue 10 is curved from one side of the plate 9 and is adapted to snap into the groove 6, thereby to hold the sides of the device against spreading apart. 70

In practice this device is stamped out of a single piece of sheet metal of a resilient nature, the article when stamped being indicated in Figure 4. The side plates 1 are then 75 bent along the dotted lines 11 so that the sides 1 will be supported substantially parallel with the web 2 constituting the back of the holder. The resiliency of the device will serve to hold the studs 4 normally pressed 80 into the depressions 5 but it will be apparent that the members 1 can be sprung apart if desired so as to space the studs from the recesses. The web 2 does not extend to the ends of the sides 1 but terminates inwardly 85 therefrom so as to leave terminal slots 12. After the parts have been shaped and bent as described the clip 9 is applied and will serve not only to prevent the holder from spreading but also to retain keys in the 90 holder.

In use the clip tongue 10 is disengaged from the groove 6 and the sides 1 of the holder are sprung apart so as to space the studs 4 from the recesses 5. The eye portions E of keys K are then placed on the studs between the sides 1 after which the sides are permitted to spring toward each other to replace the studs 4 within the recesses 5. Clip 9 is then snapped into place. 100 With the parts thus positioned the free ends of the keys will be extended between the web 2 and the plate 9 of the clip so that the keys cannot be swung out of the holder. The eye portions E of the keys, however, will extend through the slots 12. Thus when it is desired to use one of the keys the clip is disengaged from the groove 6 and one of the projecting portions of the eye E of the key to be used is pressed into the holder. This 110

will cause the shank of the key to swing out of the holder where it can be easily grasped. by holding the members 1 in the hand with the key uppermost, the projected key will be 5 in proper position for insertion into a lock. After the key has been used it can be dropped back into the holder and the clip again snapped into place.

The outer surfaces of the sides 1 can be arranged to receive suitable advertising matter 10 and it will be obvious that, if desired, any finishing material of wood, celluloid or the like can be placed on the outer surfaces of the sides 1.

15 What is claimed is:

A key holder formed in a single piece of resilient material bent to provide side members and a connecting web constituting the

back of a holder and constituting key retaining means, there being slots beyond the ends 20 of the web, key engaging means upon one of the side members and normally yielding pressed against the opposed side member, a clip connected to one of the side members and detachably engaging the other side member, said clip and web cooperating to confine 25 a key within the holder, the clip constituting means for preventing the side members of the holder from moving apart, the slots constituting means for the reception of the eye 30 portion of an engaged key when the key is in confined position.

In testimony that I claim the foregoing as my own, I have hereto affixed my signature.

BENJAMIN F. COPP.
